Primary Examiner — Marissa J Cash(74) *Attorney, Agent, or Firm* — Kevin Schraven; Anooj Patel; Hankin Patent Law, APC(57) **CLAIM**

The ornamental design for a vaporizer, as shown and described.

DESCRIPTION

FIG. 1 is a top perspective view of a vaporizer showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines in the drawings depict portions of the vaporizer that form no part of the claimed design.

1 Claim, 4 Drawing Sheets# US D856,575 S
